TREE PRUNER

Luke S. Stripling, Amarillo, Tex.

Application December 1, 1936, Serial No. 113,683

3 Claims. (Cl. 30—245)

This invention relates to pruning devices and has special reference to a tree pruner.

One important object of the invention is to provide a novel and improved construction of tree pruner which may be adjusted to different lengths.

A second important object of the invention is to provide a novel clamping means in such a pruner whereby the implement may be held at any length to which it is adjusted.

A third important object of the invention is to provide a novel arrangement of clamps and braces for such a pruner wherein the clamps act as struts for the brace rods or wires.

A fourth important object of the invention is to provide novel cutting jaws for such a pruner.

A fifth important object of the invention is to provide novel actuating means for such a pruner.

A sixth important object of the invention is to provide novel means for adjusting the actuating means to correspond with the length to which the pruner is adjusted.

A seventh important object of the invention is to provide novel means for drawing a twig or branch of a tree into the jaws and there holding it during the cutting operation.

With the above and other objects in view as will be hereinafter apparent, the invention consists in general of certain novel details of construction and combinations of parts hereinafter fully described, illustrated in the accompanying drawing and specifically claimed.

In the accompanying drawing like characters of reference indicate like parts in the several views, and:

Fig. 1a is an elevation of the upper part of the implement.

Fig. 1b is an elevation forming a continuation of Fig. 1a and showing the lower part of the implement.

Fig. 2a is a view of the parts shown in Fig. 1a but at right angles thereto.

Fig. 2b is a view of the parts shown in Fig. 1b but at right angles thereto.

Fig. 3 is a detail elevation from the left side of Fig. 2b and showing a certain pawl and ratchet device used herein.

Fig. 4 is an enlarged section on the line 4—4 of Fig. 1a.

Fig. 5 is a view showing a portion of the jaw actuating means removed from the remainder of the device.

Fig. 6 is a detail broken section on the line 6—6 of Fig. 1a.

In the present drawing illustrating the device

it is to be understood that the proportions are not a feature of the invention and that these proportions and the forms of various parts may be changed to suit constructive requirements. For instance the supporting tubes may be made much longer in proportion to their diameters, the jaws may be made smaller or larger in proportion to the other parts and may be of any form found by experience to be desirable. Thus the drawing is to be understood as merely typical of the invention.

As here shown there is provided a jaw fork 10 of tubular form and having a slot at its upper end to provide a pair of form arms 11. Through the upper ends of the arms 11 passes a pivot bolt 12 whereon is pivoted the jaw members indicated in general at A. Each of these jaw members includes an upper portion 13 preferably having a serrated inner and cutting edge 14. Extending across each other from the lower ends of the portions 13 are handle members 15, these members being pivotally mounted at their intersection on the bolt 12. Extending down from the cross-portions 15 are tail portions 16 each provided with a series of openings 17 for purposes presently to be explained. Preferably the portions 13, which may be termed the blades, are made from shear steel while the portions 15 and 16, which may be termed the jaw or cutter handles, are made from less expensive material. The blades are fixedly attached to the handles by any suitable means, such as welding or the like, as is commonly done in the manufacture of tools of the scissors type. If preferred each entire jaw may be made of high carbon steel with the parts 13 alone tempered for cutting.

Through a selected hole 17 of each jaw passes a pivot bolt 18 and each bolt also passes through a suitable bolt hole in a toggle arm 19 and the arms 19 have their inner ends connected within the member 10 by pivot bolt 20. It is here to be noted that wherever desired the bolts used herein may have thumb nuts or may be provided with lock-washers, cotters or the like to prevent accidental loosening or loss. It is not, however, deemed necessary to show or refer further to such parts as their use for the desired purposes is well known to all those skilled in the art. Below the section 10 is an intermediate tubular section 21 which is connected to the lower end of the member 10 by a coupling 22 of the usual pipe threaded type. Between the proximal ends of the members 10 and 21 is held a guide washer 23 which fits within the coupling 22 and is pressed at its periphery by said members 10 and 21 so that the

washer 23 is thus held firmly in place. In this washer is a slot 24 through which passes an upper pull bar 25 having its upper end mounted on the bolt 20. Surrounding the bar 25 is a coiled compression spring 26 which bears at its lower end on the washer 23 and at its upper end against the inner ends of the toggle arms 19. By this action the jaw handles are urged apart and by properly positioning the bolts 18 the extent of their movement apart may be regulated.

The lower end of the tube 21 fits into the upper end of a split main tube 26 having a slot 27 extending from end to end thereof. Around the end parts of the tube 26 extend clamp straps 28 and centrally between the straps 28 is a third clamp strap 29. Each of these straps is provided with spaced ears 30 through which passes a bolt 31 provided preferably with a wing or thumb nut. It will be observed that the ears of the straps 28 lie on the slotted side of the tube 26 while the ears of the strap 29 lie on the opposite side of said tube. A pair of truss wires or rods 32 have their ends connected to the bolts of the clamps 28 and their middle portions extended over the bolt of strap 29. Thus the ears on these straps 28 and 29 form struts for the truss rods or wires 32. These truss wires are for the purpose of trussing the tube against flexure when in use.

Clamped in the lower end of the tube 26 is a lower tubular member 33 and to the lower part of the member 33 are bolted or otherwise secured a pair of frame sides 34 which extend below the tube 33 to form a frame wherein is journaled a winding shaft 35. These frame sides come together as at 36 and are there held by bolts 37. The shaft 35 is provided with an operating crank 38. Fixed to the shaft 35 is an eye 39 to which is attached one end of a chain 40. The bar 25 is provided with a series of spaced bolt holes 41. A lower pull bar 42 is similarly provided with bolt holes 43 and through selected holes in the two bars passes a bolt 44. Thus the effective length of the two pull bars may be regulated by shifting the bolt from one hole to another. Obviously two or more bolts may be used to connect the bars 25 and 42 if desired. At the lower end of the bar 42 is mounted a split link 45 which may be caused to engage any link in the chain 40 in accordance with the adjustment of the group of tubular members for length. For the purpose of affording access to the split link 45 and chain 40 it is noted that the slot 27 is made of sufficient width to allow the chain and link 45 to pass therethrough. This enables the effective length of the chain to be readily adjusted. On the shaft 35 is fixed a ratchet 46 which is engaged by a pawl 47 pressed by a spring 48 so that when the chain is wound on the shaft it will be held in wound condition until the pawl be raised by the finger of the user. Also, sleeves 49 may be mounted on the shaft 35 to increase the diameter of the winding drum and thus cause the device to operate more quickly. This is advantageous in trimming twigs and small limbs when speed is desirable and so much power is not needed as is the case when larger limbs are to be cut.

Fixed to one of the toggle arms 19 is a hook member 50 which extends up beside one jaw as in Fig. 1a. When the toggle arms are pulled down by turning the crank 38 the upper end of this hook moves inwardly and downwardly so that it will hook over a twig or branch between

the jaws A and pull the same down to proper position for cutting and there hold it.

One frame side 34 is extended as at 51 and is then curved first in one direction as at 52 and then bent back to lie parallel to the portion 52 as at 53. This part 53 is preferably padded and, in using the implement, rests against the user's abdomen.

A suitable shoulder strap (not shown) may be used to hold the part 53 from slipping downwardly. Also additional bolt holes 54 may be provided for the bolt 12 so that the jaws may be brought closer together.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a tree pruner, a supporting pole including a series of telescopically adjustable sections, a pair of cutting jaws at the upper end of the pole, operating means for said jaws including pull means housed entirely within said pole, said pull means being provided with a plurality of elements adjustable longitudinally of each other and having coacting means for securing them in adjusted relation, one of said telescopic sections being longitudinally slotted to permit access to the said coacting means, the element at the lower end of the pull means being a chain and the element above the chain forming a hook for selectively engaging the links of the chain, a winding drum supported from the lower end of said pole and having one end of the chain attached thereto, and a crank for rotating said winding drum.

2. In a tree pruner, a supporting pole including a series of telescopically adjustable sections, a pair of cutting jaws at the upper end of the pole, operating means for said jaws including pull means housed entirely within said pole, said pull means being provided with a plurality of elements adjustable longitudinally of each other and having coacting means for securing them in adjusted relation, one of said telescopic sections being longitudinally slotted to permit access to the said coacting means, means at the lower end of the pole for exerting stress on the pull means, clamping bands extending around the said slotted section at the ends and middle thereof, said clamping bands having each a pair of spaced ears and a clamping bolt passing therethrough, the ears on the end bands being on one side of the section and the ears on the middle band being diametrically opposite thereto, and truss wires fastened to the bolts of the end band and extending over the bolt of the middle band.

3. In a tree pruner, a supporting pole including a series of telescopically adjustable sections, a pair of cutting jaws at the upper end of the pole, operating means for said jaws including pull means housed entirely within said pole, said pull means being provided with a plurality of elements adjustable longitudinally of each other and having coacting means for securing them in adjusted relation, one of said telescopic sections being longitudinally slotted to permit access to the said coacting means, the element at the

lower end of the pull means being a chain and the element above the chain forming a hook for selectively engaging the links of the chain, a winding drum supported from the lower end of said pole and having one end of the chain attached thereto, a crank for rotating said winding drum, clamping bands extending around the said slotted section at the ends and middle there-

of, said clamping bands having each a pair of spaced ears and a clamping bolt passing therethrough, the ears on the end bands being on one side of the section and the ears on the middle band being diametrically opposite thereto, and 5 truss wires fastened to the bolts of the end band and extending over the bolt of the middle band.
